UNITED STATES PATENT OFFICE.

WILLIAM STANLEY, JR., OF GREAT BARRINGTON, MASSACHUSETTS, AS-
SIGNOR TO GEORGE WESTINGHOUSE, JR., OF PITTSBURG, PA.

AUTOMATIC CUT-OUT FOR ELECTRIC-LIGHT CIRCUITS.

SPECIFICATION forming part of Letters Patent No. 349,613, dated September 21, 1886.

Application filed December 19, 1885. Serial No. 186,161. (No model.)

To all whom it may concern:

Be it known that I, WILLIAM STANLEY, Jr., a citizen of the United States, residing in Great Barrington, in the county of Berkshire, and 5 State of Massachusetts, have invented certain new and useful Improvements in Automatic Cut-Outs for Electric-Light Circuits, of which the following is a specification.

My invention relates to the class of apparatus employed for automatically interrupting the connections of an electric circuit when traversed by currents of abnormal strength.

The invention is especially designed to be employed in connection with an electric-light 15 system in which currents of a given potential are converted into currents of a different potential through the instrumentality of an induction-coil or inductorium.

The object of the invention is to provide an 20 electro-magnetic device operated by a current of abnormal strength in the secondary or translating circuit of the inductorium to automatically interrupt the connections of the primary circuit.

25 The invention consists in normally completing the circuit-connections from the source of electricity in a converter or translating system with the primary coil of the inductorium or converter through an automatic circuit-interrupting device which is capable of being operated to sever such connections through the instrumentality of a releasing device included in the secondary circuit of the inductorium. This device is not in any manner affected by currents of the strength which are normally designed to traverse the secondary or translating circuit, but will be acted upon by currents of abnormal or dangerous strength to operate the circuit-interrupting device, and thereby release 40 a movable arm from a detent, the action of which is to immediately sever the connections of the primary circuit.

The accompanying drawing is a side elevation of an apparatus embodying the essential 45 features of the invention, illustrating the circuit-connections in diagram.

Referring to the figure, L' L² represent a main line proceeding from any suitable source, A, of electricity, and B represents an inductorium 50 or converter. The primary coil b' is included in circuit with the main line L' L², its connec-

tions being as follows: from the section L' of the main line, through a conductor, 1, to one terminal of the primary coil b' of the inductorium B, thence by a conductor, 2, to a pivoted 55 lever, c', thence through a contact spring or brush, c², carried by the lever to a contact-plate, c³, against which the brush normally rests. The plate c³ is connected by a conductor, 3, with the sections L² of the main-line conductor. A spring, c⁴, tends to draw the brush c² from the plate, and to thus interrupt the connections of the primary. It is prevented, however, from so operating by a strip, C, of fusible metal, which constitutes a portion of 65 the secondary circuit 11 12 of the inductorium or converter, and through which the currents developed in the secondary coil b² ordinarily pass. The currents of the strength normally employed for operating the translating devices 70 in the secondary circuit do not affect the fusible strip; but a current of abnormal strength will develop sufficient heat in traversing the strip C to fuse it. The lever thereupon responds to the tension of the spring c⁴, and withdraws the spring c² from its plate c³, thereby 75 interrupting the connections of the main line through the primary circuit.

It is evident that there may be various mechanical modifications in the method of employing this safety-strip of fusible metal for accomplishing this same result, and that these may be adopted without departing from the spirit of my invention.

The application of the cut-out has been de- 85 scribed in connection with the primary coil in such manner that it operates to sever the connections of the conductor leading thereto. It is evident, however, that a shunt-circuit might be formed around the coil by the cir- 90 cuit-controller, if desirable. Thus a second contact-point may be applied to the contact arm or lever in such position that the lever rests against it when freed by the device in the secondary circuit, as indicated in dotted 95 lines.

In another application of even date here- 100 with, Serial No. 186,163, I have described and claimed another device for similar purposes operated by electro-magnetism produced by abnormal currents.

I claim as my invention—

1. The combination, substantially as herein-before set forth, with the primary circuit of an induction-coil, of a secondary circuit therefor, translating devices in the secondary circuit, a 5 fusible strip, also included in the secondary circuit, and a circuit-interrupting device for the primary circuit normally restrained by said fusible strip, but released by the melting of said strip.
- 10 2. The combination, substantially as herein-before set forth, with the primary circuit of an induction-coil, of its secondary circuit, translating devices in the secondary circuit, and a device responding to the heat developed by an 15 abnormal current in the secondary circuit for interrupting the connections of the primary circuit.

3. The combination, substantially as herein-before set forth, with the primary circuit of an induction-coil, and translating devices in the 20 secondary circuit, of a stationary and a movable contact-point, through which the connections of said circuit are normally completed, and a fusible strip normally holding said movable contact-point in contact with said stationary contact-point, which strip is included in the secondary circuit of said induction-coil. 25

In testimony whereof I have hereunto subscribed my name this 4th day of December, A. D. 1885.

WILLIAM STANLEY, JR.
